UNITED STATES PATENT OFFICE

AUGUST JIPP, OF SPANDAU, NEAR BERLIN, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

TELEGRAPH OR TELETYPE PLANT

Application filed February 18, 1929, Serial No. 340,882, and in Germany February 18, 1928.

The invention relates to improvements in telegraph or teletypewriter (writing) plants, in which the connection of the individual subscribers' stations is effected by means of automatic selectors provided at one or a plurality of exchanges.

In such plants it was hitherto necessary to transmit the current impulses for breaking the connection over a special line not used 10 during the selector or telegraph operation, in order to enable the necessary differentiation to be made between the current impulses for the various purposes (selector, telegraph, selector resetting impulse) used in the operation of the plant.

To enable the resetting of the selectors to be made over the lines used for the selector and telegraph operation, according to my invention the resetting of the automatic 20 selectors takes place by impulses, the conditions or nature of which (such as the type of current, frequency) are different from those of the selector or telegraph currents.

In this way it is possible to manage even 25 with two conductors only of an ordinary telephone cable line, audio frequency or sub-audio frequency communication being preferably used in view of the telephone service, which also allows multiplex utilization 30 of the lines.

The different condition of the selector resetting currents may, for instance, be attained by employing alternating current in contrast with the direct current of the selector or telegraph currents mentioned. It is also possible to use alternating current for 35 all the current impulses, the selector resetting alternating current being of different, preferably higher, frequency. The difference may also be produced by choosing return 40 impulses of greater duration than the two other kinds of operating impulses.

Taking into account that the telegraph 45 impulses are only of short duration and that for this purpose the armatures of the transmitter and receiver relays leave their inoperative or rest position temporarily to pass into the operative or working position, a difference in the duration of the impulses may 50 be effected by bringing the armatures after

the termination of telegraphic traffic i. e. after the return into the inoperative position permanently into the operative position, whereby a permanent impulse is given, which 55 is utilized for the tripping of the resetting relay and, if necessary of other parts of the apparatus, such as a switchgear controlling the driving motor. The armatures are thus brought into a "false" position of rest differing from the true position of rest. Since 60 polarized relays mainly come into account, the armatures remain in the false position of rest even after switching off the total operating current and the giving up of this 65 position when the current is switched on again may also be used for releasing operations on the receiving side. The throwing of the relay from the false into the true position of rest is preferably effected by a condenser impulse released on switching on the 70 motor of the telegraph apparatus, which excites an auxiliary winding of the transmitter relay and throws its armature over, whereby the receiving relay is also changed over and 75 a pre-selector switched in. After this pre-selection, which takes place automatically, the subscriber may proceed to select with his dial. In order to maintain the connection, while the telegraph relay is in its true position of rest or vibrates synchronously with 80 the telegraph or selector impulses, retarding means, such as slow-acting relays, are employed which, while the armature is in the false position of rest, are not excited and 85 maintain the circuit closed for the duration of the connection. The slow-acting relay closes the circuit of the pre-selector for the duration of the connection and when de-excited releases in well known manner the 90 tripping devices of the pre-selector and the other line selectors.

Two embodiments of my invention are diagrammatically illustrated in the drawings affixed hereto and forming part of my 95 specification. In the drawings,

Fig. 1 is a simplified diagram of connections of an exchange according to my invention, and

Fig. 2 is a diagram of my improved arrangement of relays.

In telegraphy various transmitting systems are used. The most important ones are the diplex system (1), the duplex system (2), and the duplex-diplex system (3). All these systems have, however, the resolution in the local circuit in four lines in common, one pair of which transmits messages in one direction and the other pair in the opposite direction. A fifth unsymmetrical conductor 10 serves only for secondary purposes of the internal automatic connection. If the selector apparatus is thus carried out for four lines, all the systems may be connected to the network and communicate with one another, as far as the connecting through in the automatic exchange is concerned. Referring to Fig. 1 of the drawings the three above described systems 1, 2, 3 have been assumed as subscribers.

20 The subscriber's station is diagrammatically indicated in each case by a transmitting relay S_1 with contacts s , and a receiving relay E_1 with contact e_1 . The corresponding apparatus which is connected to the subscriber's station by trunk lines L is indicated by the reference letters S_2 or E_2 respectively. The subscriber's station 2 possesses the usual line balance N .

For sending out selector impulses by the subscriber, there is provided at the subscriber station a number dial D which controls the alternating contact d upon operation of the dial and the alternating contact d_2 upon release of the dial. The contact d_1 operates to disconnect the sending relay S_1 , during the selection, from the contact T controlled by the teletypewriter apparatus; and to connect such relay with the impulse contact d_2 . A two-pole reversing switch A is arranged in the circuit 30 of relay S_1 and has the function of connecting a source of alternating current B with such relay at the completion of a message to effect release of the selector. The letter R indicates the receiving magnet of the teletypewriter apparatus.

If upon release of the rotated dial D selector impulses are sent to the automatic exchange by the oscillating movement of the contact d_2 over the relay S_1 and the conduit L , the operating magnet H_1 at such exchange is intermittently excited corresponding to the selector impulses through the medium of the contact l_2 of the receiving relay E_2 . The armature h_1 of the magnet H_2 then starts the selector consisting of five rows of contacts (i, k, l, m) and contact brushes. Assuming that three impulses have been dispatched, the brushes of the selector set themselves on the contacts 3. In the manner usual in automatic selectors the connecting through relay P_1 is instantaneously excited across the row of contacts n and the C-conductors every time one of the contacts 1 to 3 is touched. Since 40 this relay P_1 is designed as slow-acting relay,

it only responds when the brush stops on the contact selected.

If the line selected was found to be engaged the relay could not respond, since the connecting through relay of the occupied selector would be connected in parallel to the newly incoming relay, so that in consequence of the dividing of the current such a weak current only is available for each relay, that the armature can be maintained in the attracted 70 position, but cannot be pulled up from the position of rest.

The connecting through relay P_1 now connects the four lines a, b, d, e of the selecting stations to the brushes i, k, l, m by closing its contacts P_1a, P_1b, P_1d and P_1e . Since the brushes rest upon the contacts 3 and these are in their turn connected to the multiplex lines of the subscriber 3, the transmission of messages may commence without the telegraph 80 impulses now sent over the line, which are of the same kind as the selector impulses, affecting the selectors. This is attained by the relay Q_1 being excited across the closed contact p, f , lines o and c and the relay Q_2 through the winding of the relay P_1 whereby its contacts q_1 and q_2 disconnect the switching magnets H_1 and H_2 of the selectors 1 and 90 3 from the lines a, b of the subscribers connected at the time.

When the communication has come to an end, the double pole switch A , which may be in the form of a key, is temporarily reversed by one of the subscribers, whereupon the sending relay S_1 is disconnected from the sending and selector contacts and is connected with the source of alternating current B . The alternating current thus sent out has a frequency different from that of the telegraph frequency and brings into action, over the 100 sending relay S_1 , conductor L and receiving relay E_2 , the resonance relay W_1 located in the automatic exchange; the relay W_1 is permanently connected in these lines and is preferably connected through a condenser C in 110 known manner. The relay W_1 thereupon closes, through its armature w_1 , a circuit for the releasing magnet M_1 which, upon attracting its armature, releases the latching element which holds the selector. The latter then returns to its initial position under the influence of a spring; the relays W and P are thus deenergized and the operating magnet H_1 is again connected to the conductors 120 a, b through q_1 , so that the mechanism is again in its original position.

Fig. 2 illustrates diagrammatically a relay, in which the resetting device of the loaded selectors is released by the application of the "false" position of rest. In this figure W is the winding of a telegraph receiving relay with the working contact a and the idle contact r . Both contacts are connected to a pole each of a battery B , the centre of which is grounded.

The armature of the relay is alternately pulled against one or the other of the contacts by telegraphic impulses, so that a current of alternating direction is closed in well known manner. The working contact upon which rests the relay during the "false" idle position is bridged by the winding V of a slow-acting relay. The slow-acting relay whose contacts, not shown, control in well known manner a pre-selector and the tripping device of further selectors, is thus short-circuited in the "false" idle position of the receiving relay W. When the receiving relay is excited its armature is pulled against the true idle contact r, whereby the slow-acting relay is connected to the battery B and excited. Its contacts complete the pre-selector circuit and also maintain it closed during the oscillation of the armature between the contacts a and r due to the retarding action. The subscriber after having finished the pre-selection may thus continue to select with his dial apparatus and then telegraph. When the transmission is finished and the subscriber sends the clearing impulse over the line, for instance by switching off his motor, the armature of the relay W is finally and for a considerable time pulled against the contact a into the false position of rest, so that by the dropping off of the slow-acting relay contacts the selectors are reset into the initial position and the connection is broken.

Various modifications and changes may be made without departing from the spirit and the scope of the invention, and I desire, therefore, that only such limitations shall be placed thereon as are imposed by the prior art.

I claim as my invention:

1. A telegraph or teletyper system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, and devices at each of said exchanges for releasing the said selectors at the end of a communication, said devices being operable by current of a frequency different from that of the telegraph currents.

2. A telegraph or teletyper system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, and devices at each of said exchanges for releasing the said selectors at the end of a communication, said devices including a resonance relay responsive at the frequency of an

alternating current transmitted at the end of the communication.

3. A telegraphic or teletyper system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, and devices at each of said exchanges for releasing the said selectors at the end of a communication, said devices including a resonance relay responsive at the frequency of an alternating current transmitted at the end of the communication, said resonance relay being permanently connected to said telegraphic lines.

4. A telegraph or teletyper system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, and devices at each of said exchanges for releasing the said selectors at the end of a communication, said devices being operable by a current of the same nature as that of the telegraphic impulses but of duration different from that of said impulses.

5. A telegraph or teletyper system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, devices at each of said exchanges for releasing the said selectors at the end of a communication, and a relay forming part of the telegraphing circuit and having a contact movable between a false idle position and a true idle position occupied during the operation of the system, said devices being controlled by the contact of said relay in such manner, that the release of said devices is effected upon switching such contact from the true idle position to the false idle position.

6. A telegraph or teletyper system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, devices at each of said exchanges for releasing the said selectors at the end of a communication, a polarized relay forming part of the telegraphing circuit, and a slow-acting relay having a winding bridg-

ing the contact of the polarized relay, said devices being controlled by said slow-acting relay.

7. A telegraph or teletypewriter system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, devices at each of said exchanges for releasing the said selectors at the end of a communication, and switching mechanism automatically cut in at the termination of a communication at a subscriber station, said devices being controlled by said mechanism.

8. A telegraph or teletypewriter system comprising a plurality of subscriber stations, lines for transmitting the telegraphic messages, one or more exchanges, automatic selectors at each of said exchanges for connecting said stations selectively, means located at the subscriber stations and operative to control the said selectors over the said telegraphic lines, devices at each of said exchanges for releasing the said selectors at the end of a communication, and automatic switching mechanism in said subscriber stations adapted to be cut in when the teletypewriter apparatus is at rest, said devices being controlled by said mechanism.

In testimony whereof I affix my signature.

AUGUST JIPP.
